[57] CLAIM

The ornamental design for holder for chopsticks, as shown and described.

DESCRIPTION

FIG. 1 is a perspective view of a holder for chopsticks showing my new design;
FIG. 2 is a front elevational view, the rear elevational view being a mirror image thereof;
FIG. 3 is a right side elevational view, the left side elevational view being a mirror image thereof;
FIG. 4 is a top plan view, the bottom plan view being a mirror image thereof; and,
FIG. 5 is a perspective view thereof, the broken line showing of chopsticks is environmental only and forms no part of the claimed design.

FIG. 1

FIG. 3

FIG. 4

FIG. 2
